UNITED STATES PATENT OFFICE.

JOSEPH E. WEAVER, OF TWIN FALLS, IDAHO.

PUMP.

1,115,261.

Specification of Letters Patent. Patented Oct. 27, 1914.

Application filed September 23, 1913. Serial No. 791,300.

To all whom it may concern:

Be it known that I, JOSEPH E. WEAVER, a citizen of the United States, and a resident of the city of Twin Falls, in the county of Twin Falls and State of Idaho, have invented a new and Improved Pump, of which the following is a full, clear, and exact description.

My invention relates to pumps, and has reference more particularly to balanced compound pumps of the reciprocating type provided with translating plungers and swinging, reciprocating pump members.

An object of the invention is to provide a simple, strong, durable, and efficient pump in which the power required to pump liquid is reduced to a minimum by balancing the moving parts of the pump.

The invention consists of the construction and combination of parts to be more fully described hereinafter and fully set forth in the claims.

Reference is to be had to the accompanying drawings forming a part of this specification, in which like characters indicate corresponding parts in all the views and in which;

Figure 1 is an elevation of an embodiment of my invention partly broken away to show the details of construction of the translating plungers; Fig. 2 is an enlarged vertical section of the enlargement in the translating plunger and shows the detail of connection with the swinging pump members and also the stationary inlet pipe controlling the inlet to the translating plunger; Fig. 3 is a side view in the direction of the arrow on Fig. 2; Fig. 4 is a plan view in the direction of the arrow, as shown in Fig. 2; Fig. 5 is a section on line 5—5, Fig. 6; Fig. 6 is an elevated section showing the detail of construction of the pressure equalizing mechanism; Fig. 7 is an enlarged vertical section showing the detail of construction of the swinging plunger; Fig. 8 is an enlarged vertical section of the outlet end of the translating plunger; Fig. 9 is a section on line 9—9, Fig. 6; Fig. 10 is a section on line 10—10, Fig. 9; Fig. 11 is a section on line 11—11, Fig. 3; and Fig. 12 is a section on line 12—12, Fig. 1.

Before proceeding to a more detailed description of my invention, it must be clearly understood that in place of using a large storage tank, as shown in Fig. 1, delivery

tubes can be directly associated with the outlet ends of the translating plungers.

Referring to the drawings, 13 represents a tank from the top of which leads a delivery pipe 14. The tank is supported on a platform 15 which is carried by supports 16 mounted on a base 17. The bottom 18 of the tank 13 is provided with apertures 19 bordered within the tank by a member 20 provided with a recess carrying a packing member 21. Exterior of the tank these apertures are bordered by a stuffing box 22.

Fitting snugly through the stuffing box 22 and the member 20 is a hollow plunger 23 adapted to translate vertically. The upper end of the plunger 23 is provided with apertures 24 which are always above the member 20. The end portion above the apertures 24 receives a spider member 25 rigidly secured to the plunger in any suitable way and carrying a rod 26 on which is slidably mounted a massive valve member 27. The rod 26 is provided with a head 28 forming a stop for the downward motion of the valve 27, while the central portion of the spider member 25 forms a stop for the upward motion of the valve 27.

The plunger 23 at the end lying outside of the tank 13 is provided with an enlarged portion 30 formed preferably of two intersecting cylindrical casings 31, the elements of which are perpendicular to lines parallel to the axis of the plunger 23, the intersection of the casing being in alignment with the axis of the plunger. Rigidly secured to the enlarged portion 30 and in alignment with the plunger 23 is a tubular member 32, which in reality forms the continuation of the plunger 23. This tubular member at 90 the end engaging the casing 31 receives a member 33 forming valve seats for valves 34 pivotally mounted on said member and forming a check valve preventing the flow of liquid from the enlarged portion 30 to 100 the tubular member 32. The valves 34 are provided with projections 35 which prevent an excessive displacement of the valves 34.

The lower end of the tubular member 32 105 engages a stationary tubular member 36 connected to the inlet pipe from where the water is pumped. This stationary tubular member 36 fits snugly into the tubular member 32 so that it forms a stationary inlet 110 pipe in the same, the end of which, leading into the tubular member 32, is provided

with a check valve 37, as used for admission valves in pumps.

The casings 31 are each provided on the lateral surface thereof with an opening 38, which is covered with a part-cylindrical section 39 fitting snugly over the lateral surface of the casing 31 and engaging with its edges guides 40 secured to the lateral surface of the same. These guides 40 prevent the part-cylindrical section from moving away from the lateral surface of the cylindrical casing 31 but allows the same to swing on the lateral surface of the casings. The lateral surface of each casing 31 is provided with a packing member 41 which surrounds the opening 38 and engages the part-cylindrical section 39, thereby preventing leakage through the contacting surfaces of the part-cylindrical section and the cylindrical casings.

The part-cylindrical section 39 is provided centrally on its lateral surface with an aperture 42 the axis of which passes through the axis of the part-cylindrical section, and which aperture receives a tubular member 43 rigidly secured thereto and forming an integral part of the part-cylindrical section 39. The axis of this tubular member necessarily passes through the axis of the cylindrical casings 31. Fitting snugly into the tubular member 43 is a tubular member 44 the non-engaged end of which is rigidly secured to a part-cylindrical section 45 similar to the part-cylindrical section 39 and fitting on to a cylindrical casing 46. This casing is also provided with a lateral opening 47 which is covered by the part-cylindrical section 45. The part-cylindrical section 45 is guided in its motion by guides 48 similar to the guide members 40 and rigid with the lateral surface of the cylindrical casing 46. The lateral surface of the casing 46 under the part-cylindrical section 45 is provided with a packing member 49 similar to the packing member 41 and for the same purpose.

The tubular member 44, which is necessarily axial with the tubular member 43, has its axis passing through the axis of the cylindrical casing 46, and, therefore, the axis of the tubular members 43 and 44 are passing through the axes of the cylindrical casing 31 and the cylindrical casing 46. The length of the lateral opening 38 in the cylindrical casing 31 and the lateral opening 47 in the cylindrical casing 46 is such that the tubular members 43 and 44 are always in communication with the interior of the casings 31 and 46 respectively, no matter what the position of those members is.

The cylindrical casings 46 are rigidly secured to the supports 16 by any suitable means. Each of these casings is provided with a central partition 50 substantially parallel to the axis of translation of the

plunger 23 and forming a reinforcement for the casings.

The hollow plunger 23 adjacent the enlargement 30 is connected to one end of a pipe 51, which pipe extends parallel to the tubular part of the plunger 23 and has its other open end within the tank 13 substantially level with the end of the hollow plunger 23. The pipe 51 is associated in its motion with the plunger 23 and is snugly fitted to the bottom of the tank 13, so as to prevent leakage. The pipe 51 adjacent its connection with the hollow plunger 23 is provided with a slide valve 52, the stem of which is engaged by the bifurcated end of a lever 53 pivotally mounted on the enlarged portion 30. Rigidly secured with the lever on a pivot is a pinion 54 adapted to be engaged by teeth 55 provided on the part-cylindrical section 39. When the pinion 54 is engaged by the teeth 55 the slide valve is in open position establishing communication between the tank and the portion of the hollow plunger 23 below the valve 27 and above the valves 34. The reason for this will appear hereinafter.

The openings 19 in the bottom of the tank 13 are so positioned as to be central between the cylindrical casings 46 carried by the support 16. This structure, as shown in Fig. 1, not only provides balanced pumps to each side of the central base 17 but it also provides balanced parts for each pump to each side of the enlarged portion 30. The two pumps as shown in Fig. 1 are actuated by the walking beam 56 secured to a shaft 57 mounted in the central base 17 and actuated by any suitable means. The ends of the walking beam engage a projection on the tubular member 32 whereby when the pump 105 is actuated the two pumps are moved in opposite directions.

The action of my pump is as follows: The right hand pump being at the end of its delivery stroke produced by the swinging, reciprocating pump members is at the same time at the end of its suction stroke, produced by the tubular member 32 and the stationary inlet pipe 36. In the beginning of its downward motion the pressure in the tank and the hollow plunger being the same the valve 27 will place itself on the head 28 by the action of gravity. During the downward motion the liquid from the tubular member 32 passes through the valve 34, 120 through the enlargements, into the tubular members 43 and 44, which increase in voluminal capacity during the downward motion of the plunger. The voluminal capacity of the telescoping tubular members 44 125 and 43 on both sides of the enlargement 30 is substantially equal to the suction produced by the tubular member 32. The pressure on the right hollow plunger 23, after the valve 27 engages the head 28, helps its 130

downward motion and also helps to balance the weight of the pump on the left. When the pump on the right arrives at the position in which the pump at the left is shown, the pinion 54 becomes engaged with the teeth 55 provided on the cylindrical section 39. This opens the slide valve 52 and establishes communication between the tank and hollow plunger below the valve 27 and above valves 34. This equalization in pressure 10 closes the valve 34. As the pump is moved upward by the beam the tubular member 44 upward by the beam the tubular member 44 enters into the tubular member 43 and reduces the volume therebetween forcing the 15 water through the enlarged section and out through the hollow plunger, thereby forcing the valve 27 above the apertures 24 and delivering the liquid through the said apertures until the same reaches the position 20 shown by the pump and the rod. It is understood that the slide valve 52 is closed at the beginning of the delivery stroke of the pumps, and the same is opened at the end of the return stroke.

Having thus described my invention, I claim as new and desire to secure by Letters Patent:—

1. In a pump, the combination of a receptacle; a plunger having a valve-controlled inlet; a valve-controlled outlet from the plunger to the receptacle; swinging pump members associated with the plunger and adapted to reciprocate when the plunger is reciprocated and thereby pump a liquid into the receptacle through said plunger.

2. In a pump, the combination of a receptacle having a valve-controlled inlet; a valve-controlled outlet from the plunger to the receptacle; swinging pump members associated with the plunger engaging the same intermediate its inlet and outlet, said swinging pump members adapted to reciprocate when the plunger is reciprocated whereby they pump a liquid through said plunger into the receptacle.

3. In a pump, the combination of a receptacle; a hollow plunger having a valve-controlled inlet; a valve-controlled outlet from said plunger to said receptacle; oppositely disposed swinging pump members engaging said hollow plunger intermediate its inlet and outlet and adapted to reciprocate to deliver liquid into said hollow plunger when said hollow plunger is reciprocated whereby liquid is pumped by said swinging pump members through said hollow plunger.

4. In a pump, the combination of an outlet pipe; means for pumping liquid through said outlet pipe comprising oppositely disposed pump members mounted to swing; a reciprocating plunger intermediate said swinging pump member and, associated therewith, said swinging pump members being adapted to reciprocate when said plun-

ger is reciprocated, whereby liquid is pumped by said swinging plunger into said outlet pipe.

5. In a pump, the combination of a receptacle, a plunger having a valve-controlled inlet thereto; a valve-controlled outlet from the plunger to the receptacle; oppositely disposed swinging pump members associated with the plunger and adapted to reciprocate to deliver liquid into said plunger when the same is reciprocated; means for reciprocating said plunger; and means for balancing the weight of the moving parts of the pump.

6. In a pump, the combination of a receptacle having a delivery pipe therefrom; a plunger having a valve-controlled outlet into said receptacle; swinging pump members associated with said plunger and adapted to pump liquid into said receptacle through said plunger; means for reciprocating said plunger whereby said swinging pump members are actuated; a valve-controlled inlet to said plunger, said plunger having means whereby the pressures in the receptacle and plunger at the end of its return stroke are equalized.

7. In a pump, the combination of a receptacle having a delivery pipe therefrom; a plunger having a valve-controlled outlet to said receptacle; a valve-controlled inlet to said plunger; swinging pump members engaging said plunger intermediate its inlet and outlet and disposed on the opposite sides of said plunger; means for reciprocating said plunger whereby said swinging pump members are caused to reciprocate in unison with said plunger; a tubular member connecting said receptacle with the plunger intermediate its inlet and outlet; and means on said tubular member for establishing communication between the receptacle and the plunger when the latter is at the end of its return stroke.

8. In a pump, the combination of a receptacle having a delivery pipe; a plunger having a valve-controlled outlet to said receptacle; a valve-controlled inlet to said plunger, swinging pump members engaging said plunger intermediate its inlet and outlet and disposed on the opposite sides of said plunger; means for reciprocating said plunger whereby said swinging pump members are caused to reciprocate in unison with said plunger; a tubular member connecting said receptacle with the plunger intermediate its inlet and outlet; and means on said tubular member, controlled by the motion of the plunger, for establishing communication between the receptacle and the plunger at the end of its return stroke, whereby the pressures in the receptacle and said plunger are equalized.

9. In a pump, the combination of a receptacle; a hollow plunger having a valve-con-

- trolled inlet; a valve-controlled outlet, said plunger having an enlarged portion intermediate said inlet and outlet; oppositely disposed swinging pump members engaging said enlarged portion; means for reciprocating said plunger whereby said swinging pump members are reciprocated in unison with said enlarged portion; and means establishing communication between said receptacle and the plunger when the same is at the end of its return stroke.
10. In a pump, the combination of a receptacle; a hollow plunger having a valve-controlled inlet; a valve-controlled outlet, said plunger having an enlarged portion intermediate said inlet and outlet; oppositely disposed swinging pump members engaging said enlarged portion; means for reciprocating said plunger whereby said swinging pump members are reciprocated in unison with said enlarged portion; and means establishing communication between said enlarged portion and said receptacle when the swinging pump members are at the end of their suction strokes.
11. In a pump, the combination of a receptacle; a hollow plunger having a valve-controlled outlet at one end engaging said receptacle and a valve-controlled inlet at the opposite end, said plunger having an enlarged portion composed of cylindrical parts the elements of which are perpendicular to lines parallel to the axis of the plunger; a tubular member mounted to oscillate on one of said cylindrical parts and in communication therewith; a swinging pump member engaging said tubular member and reciprocating therein when said plunger is reciprocated.
12. In a pump, the combination of a receptacle; a hollow plunger having a valve-controlled outlet at one end engaging said receptacle and a valve-controlled inlet at the opposite end, the plunger having an enlarged portion composed of cylindrical parts the elements of which are perpendicular to lines parallel to the axis of the plunger; part-cylindrical sections mounted to oscillate on the lateral surface of said enlarged portion; tubular members radiating from the centers of said cylindrical parts rigidly secured to said part-cylindrical sections; means in said cylindrical parts and sections establishing communication between said tubular members and said enlarged portion; pump members mounted to swing engaging said tubular portions; means for actuating the hollow plunger whereby said swinging pump members are actuated and thereby pump liquid through said hollow plunger into the receptacle.
13. In a pump, the combination of a receptacle; a hollow plunger having a valve-controlled outlet at one end engaging said receptacle and a valve-controlled inlet at

the opposite end, said plunger having an enlargement formed of two intersecting cylindrical casings the elements of which are perpendicular to lines parallel to the axis of the plunger and the intersection of which casings lies in alinement with the axis of the plunger, said cylindrical casings having oppositely disposed lateral openings; part-cylindrical sections mounted to oscillate on the lateral surfaces of said casings and covering said lateral openings; tubular members on said part-cylindrical sections radiating from said casings and communicating therewith through the lateral openings in said casings; pump members mounted to swing engaging said tubular members; and means for actuating the hollow plunger whereby said swinging pump members are actuated, substantially as and for the purpose set forth.

14. In a pump, the combination of a receptacle, a hollow plunger having a valve-controlled outlet at one end engaging said receptacle and a valve-controlled inlet at the opposite end, said plunger having an enlargement formed of two intersecting cylindrical casings the elements of which are perpendicular to lines parallel to the axis of the plunger and the intersection of which casings lies in alinement with the axis of the plunger, said cylindrical casings having oppositely disposed lateral openings; part-cylindrical sections mounted to rotate on the lateral surfaces of said casings and covering said lateral openings; tubular members on said part-cylindrical sections radiating from said casings and communicating therewith through the lateral openings in said casings; a second tubular member engaging each of the first-mentioned tubular members; means whereby said second-mentioned tubular member may be oscillated; and means for actuating the hollow plunger whereby said tubular members are actuated, substantially as and for the purpose set forth.

15. In a pump, the combination of a receptacle; a hollow plunger having a valve-controlled outlet at one end engaging said receptacle and a valve-controlled inlet at the opposite end, said plunger having an enlargement formed of two intersecting cylindrical casings the elements of which are perpendicular to lines parallel to the axis of the plunger and the intersection of which casings lies in alinement with the axis of the plunger, said cylindrical casings having oppositely disposed lateral openings; oppositely disposed cylindrical casings; telescoping tubular members connecting said second-mentioned cylindrical casings with said intersecting cylindrical casings, said telescoping members being mounted to swing on said cylindrical casings; and means for actuating the hollow plunger and whereby

said telescoping members are actuated, substantially as and for the purpose set forth.

16. In a pump, the combination of a receptacle having a delivery pipe; a hollow plunger having a valve-controlled outlet at one end engaging said receptacle and a valve-controlled inlet at the opposite end, said plunger having an enlarged portion formed of two intersecting cylindrical casings, the elements of which are perpendicular to lines parallel to the axis of the plunger and the intersection of which lies in alinement with the axis of the plunger; cylindrical casings one to each side of said hollow plunger; diametrically disposed reinforcing members in said second-mentioned cylindrical casings which are substantially parallel to the axis of the hollow plunger; telescoping tubular members

connecting the intersecting casings with the second-mentioned casings; means establishing communication between said intersecting cylindrical casings and the second-mentioned casings through the medium of said telescoping tubular members; means for mounting said telescoping tubular members to oscillate on said casing; and means for actuating the hollow plunger whereby said telescoping tubular members are actuated for the purpose substantially as set forth. 30

In testimony whereof I have signed my name to this specification in the presence of two subscribing witnesses.
